UNITED STATES PATENT OFFICE

129,200

DESIGN FOR AN ELEVATED RAILWAY STATION UNIT

John O. Heinze, Detroit, Mich.

Application April 13, 1940, Serial No. 91,648

Term of patent 14 years

To all whom it may concern:

Be it known that I, John O. Heinze, a citizen of the United States, residing at Detroit, in the county of Wayne and State of Michigan, have invented a new, original, and ornamental Design for an Elevated Railway Station Unit, of which the following is a specification, reference being had therein to the accompanying drawings, forming part thereof.

Fig. 1 is a top plan view of a portion of an elevated railway station unit showing my new design;

Fig. 2 is a side elevational view thereof;
Fig. 3 is a transverse sectional view on the line 3—3 of Fig. 2; and

Fig. 4 is a perspective view of the complete unit of the elevated railway station unit of my design.

I claim:

The ornamental design for an elevated railway station unit, as shown.

JOHN O. HEINZE.
